Primary Examiner — Ian Simmons*Assistant Examiner* — Charles Hanson(74) *Attorney, Agent, or Firm* — Lerner, David, Littenberg, Krumholz & Mentlik, LLP(57) **CLAIM**

The ornamental design for stent connections, as shown and described.

DESCRIPTION

FIG. 1 is a top perspective view of stent connections showing my new design;

FIG. 2 is a front side elevational view thereof;

FIG. 3 is a rear side elevational view thereof;

FIG. 4 is a right side elevational view thereof, the left side elevational view being a mirror image of the right side;

FIG. 5 is a top plan view thereof;

FIG. 6 is a bottom plan view thereof;

FIG. 7 is an enlarged perspective view of a feature thereof shown in FIG. 2; and,

FIG. 8 is an enlarged perspective view of a feature thereof shown in FIG. 2.

It is noted that any broken line illustration of environmental structure in the drawing is not part of the claimed design.
